COMPRESSIBLE BULB OPERATED LIQUID DISPENSER

Harry A. Dieffenbach, Glen Olden, Pa.

Application January 27, 1948, Serial No. 4,623

1 Claim. (Cl. 222—207)

1

This invention relates to dispensing device and more particularly to a device for dispensing liquids.

The object of the invention is to provide an improved and simplified liquid dispenser which permits a selective range both in the amount dispensed and the direction of application and is particularly useful in connection with the dispensing of disinfectants and the like.

The invention consists in the novel construction arrangement and combinations of parts as hereinafter more particularly described and claimed.

One sheet of drawings accompanies this specification as part thereof in which like reference characters indicate like parts throughout.

In the drawings:

Fig. 1 is a side elevation, partly in cross section;

Fig. 2 is a fragmentary view of the upper end of the standard shown partly in cross section;

Fig. 3 is a vertical transverse cross section through a modified form of the invention; and

Fig. 4 is a longitudinal cross section through the intake check valve.

The present invention is directed to a dispensing device for liquids and more particularly chemicals, and various parts can be constructed of suitable materials, metals, plastics or the like, as may appear desirable in connection with the particular liquid to be dispensed.

In accordance with the present invention, a container 1 is provided as a reservoir for the liquid to be dispensed, having a compartment 2 and as herein illustrated a removable cover 3 with a threaded orifice and cap 5 through which additional liquid can be introduced.

A tubular standard 8 is passed through the cover 3 and secured thereto as by a threaded ring 7 secured on the standard 8 and engaging a similarly threaded orifice in the cover. The bottom of the standard 8 is steadied by being inserted in a circular flange 6 formed on the bottom of the container.

The upper end of the standard 8 is closed by a cap 9, a portion of which extends within the tube 8 and is provided with an annular groove 10 within which a screw 11 threaded through the standard 8 is adapted to engage, thus permitting rotation of the cap with respect to the standard but preventing sliding movement of the cap except where it is desired to remove the cap which is permissible by removal of the screw 11. The cap 9 has an axial orifice 12 within which is rotatably seated the upper end of a tube 13 and in

10 this passage 12 is threaded one end of a dispensing tube 26 which is preferably bent to extend at an angle with respect to the standard 8.

The tube 13 extends downwardly through the standard 8 and through a lateral orifice 14 adjacent the bottom of the standard and is connected with an inlet check valve 40 positioned within the compartment 2 and adjacent the bottom of the container 1. The inlet check valve 40 is further connected with an additional tube 13' which extends through a wall of the container and has secured on its outer end a compressible bulb 15.

15 The check valve 40 is of conventional construction comprising a body having a through orifice with two valve seats 28' and 30' with which valve seats are associated balls 28 and 30, the arrangement being such that upon compression of the bulb 15 liquid will be forced through the tube 13 and through the outlet discharge tube 26. Release and expansion of the bulb 15 introduces a new charge of liquid from the container through the inlet port 27.

20 Supported by the container is a housing for the compressible bulb 15, comprising a bottom 16 and a hinged wall or cover 17 pivoted with respect to the container as by pivots 18. The rocking of the pivoted cover 17 may be controlled by set screws 21 threaded through flanges 20 formed on the housing and engaging lugs 19 formed on the cover 17.

25 With the structure thus described and illustrated in Fig. 1, it will be apparent that the discharge tube 26 is disposed annularly with respect to the standard 8 in any direction as desired and that pressure of the foot upon the hinged lid 17 will cause the discharge of a predetermined amount of the liquid through discharge pipe 26.

30 In the modified form of the invention illustrated in Fig. 3, the container is formed with a back wall 31 in the form of a bracket adapted to be secured to a wall and the housing for the compressible bulb 15 is preferably located below the bottom of the container 1' so that the hinged cover 17 can be manipulated by hand. In this form of the invention, the tube 13' is extended directly through the bottom of the container and functions as a discharge port.

35 Various modifications in the precise arrangements and construction of the parts will readily suggest themselves to those skilled in the art but within the scope of the invention as claimed.

Having thus fully described my invention, I claim:

40 Liquid dispenser comprising a container, a dis-

charge tube passing through said container having both ends opening exteriorly thereof, and having an intermediate portion within said container adjacent the bottom thereof, a shape resuming compressible bulb connected to one end of said tube, said bulb being otherwise imperforate, the other end of said tube being a discharge nozzle, a check valve within said tube opening toward said discharge nozzle, the intermediate portion of said tube having an opening below liquid level between said check valve and bulb, an inwardly opening check valve controlling said opening, a hinged operating plate sustained in normal inactive position by said bulb, and an adjustable stop spaced from that side of said plate which is in contact with said bulb, in the path of movement thereof, to be

contacted by said plate for determining the amount of liquid displaced by said bulb when said plate is pressed against said bulb.

HARRY A. DIEFFENBACH.
